UNITED STATES PATENT OFFICE.

PHILIP S. SMITH, OF NEW YORK, N. Y.

DESIGN FOR A BOX-WRAPPER OR COVERING-BLANK.

SPECIFICATION forming part of Design No. 32,740, dated May 29, 1900.

Application filed April 27, 1900. Serial No. 14,637. Term of patent 14 years.

To all whom it may concern:

Be it known that I, PHILIP S. SMITH, a citizen of the United States, residing at New York, (Brooklyn,) in the county of Kings and State of New York, have invented and produced a new and original Design for a Box-Wrapper or Covering-Blank; and I do hereby declare the following to be a full, clear, and exact description of the same, reference being had to the accompanying drawings, forming a part thereof.

My present invention consists in a new and original design for a box-wrapper or covering-blank for boxes, and is illustrated in the accompanying drawings, in which—

Figure 1 is a plan view of the blank or wrapper; and Fig. 2 is a sectional view taken on the line 2 2, Fig. 1.

The leading feature of the design consists of a blank comprising a body portion having side and end extensions, said side extensions being formed with projecting portions, as shown.

Referring to the drawings, the reference-numeral 1 designates the body portion of the blank or wrapper, which is provided with end extensions 2 and side extensions 3, each of which are formed integral with the body portion. The side extensions are both provided at opposite ends with projecting portions 4, and the corners of said projecting portions are cut away at an angle 5 to the sides of the extensions 3, as illustrated in the drawings. The opposite corners of the two end extensions 2 are also cut away at 6, as shown. 35

What I claim is—

The design for a box-wrapper or covering-blank, substantially as shown and described.

In testimony whereof I affix my signature in presence of two witnesses.

PHILIP S. SMITH.

Witnesses:

ALMA C. STERN,
H. B. SMITH.
